LOCATING DEVICE FOR PERFORATING GUNS

Thomas L. Long, Houston, Tex., assignor, by mesne assignments, to Johnston Testers, Inc., Houston, Tex., a corporation of Texas

Application January 23, 1952, Serial No. 267,851

3 Claims. (Cl. 166—219)

This invention relates to an oil well tool, and in particular to an oil well tool for locating a perforating gun in an oil well.

A main object of the present invention is to provide an oil well tool by which the location of collars in an oil well casing can be determined for the purposes of checking measurements as to depth and to correlate the depth of particular zones in the formation penetrated by the well casing to aid in laterally perforating the formation by means of a perforating gun.

A more particular object of the present invention is to provide a tool as generally described above including fingers engageable with the interior of the casing to snap into recesses provided between the adjacent ends of pipe sections, and which tool includes a mechanism for collapsing the fingers upon a predetermined upward pull on the tool to give a positive indication at the surface of the location of various collared joints.

A further object of the invention is to provide a tool as described above in which there is a mechanism for permanently collapsing or retracting the fingers to permit ready removal of the oil well tool from a well.

An additional object of the present invention is to provide an oil well tool as above described in which the operation of the mechanism for permanently collapsing the fingers is initiated by detonation of the explosive charges in the perforating gun.

Various other objects of the present invention will be apparent from the following description taken in connection with the accompanying drawings wherein:

Fig. 1 is a vertical longitudinal section through a tool embodying the concepts of the present invention and showing the fingers of the tool in engagement with the lower end of a pipe section.

Fig. 2 is a view similar to Fig. 1 but showing the fingers just after the same have been cammed off the lower end of the pipe section.

Fig. 3 is a view similar to Fig. 1 but showing the fingers as being permanently collapsed for removal of the tool from the well.

Fig. 4 is an enlarged fragmentary view illustrating the construction and mounting of one finger or feeler.

Fig. 5 is a fragmentary sectional view taken along line 5—5 of Fig. 4.

Referring to the accompanying drawings wherein similar reference characters designate similar parts throughout, a tool embodying the concepts of the present invention is shown disposed in an oil well casing generally entitled 9, there being shown an upper pipe section 11 and a lower pipe section 13 connected by a collar 15 providing a recess 17 between the lower end 11a of upper section 11 and the upper end 13a of lower section 13.

The tool includes a body 19 threadedly secured at its upper end to a perforating gun generally entitled 21. Gun 21 includes a plurality of cartridge units 23, each unit including the usual projectile and powder charge for projecting the same out into the well casing.

Between perforating gun 21 and body 19 there is a

2

suitable seal 25. For initiating the detonation of the powder charges in the perforating gun there is provided a flash passage 27 extending down through the gun and to the lower end thereof. At or adjacent the upper end of the flash passage 27 there is located a conventional mechanism such as an electrical circuit leading to the surface for initiating detonation of the charges.

Body 19 has a reduced depending tubular portion 19a having threaded on the lower end thereof a sleeve 29 locked thereon by a suitable lock or chuck nut 31, the latter having openings therethrough as shown in Fig. 1. Sleeve 29 and the lower depending portion 19a of body 19 form an upwardly opening recess for the reception of a mechanism to be now described.

Disposed around portion 19a and slidable therealong is a finger carrier generally entitled 33, in the form of a ring, having pivoted thereon by their lower ends a plurality of fingers 35 pivoting about pivots 37, which are carried in ears formed on carrier 33. Fingers 35 are spring urged outwardly by torsion springs 39 as shown in Figs. 4 and 5. Springs 39 are relatively weak in the sense that they cannot support the fingers 35 (by the creation of an upward frictional force component between fingers 35 and sleeve 29) in the position in Fig. 1 against the force of gravity acting on the carrier 33 and the fingers, so that if not otherwise supported fingers 35 and carrier 33 will descend to the position shown in Fig. 3 to be disposed substantially within sleeve 29.

For normally positioning the fingers upwardly where they can engage the interior of casing 9, there is provided a relatively strong compression spring 41 supported by a movable collar 43, the latter being held in an upward-operative position by a plurality of locking balls 45 received within openings which are formed in tubular portion 19a of body 19. Balls 45 are held in operative positions by a plunger 47 slidably received within the interior of body 19. Plunger 47 is held in a position to retain balls 45 in their locking positions by a shear pin 51 extending through body 19 and plunger 47.

Between the perforating gun 21 and the body 19, there is provided an explosive charge 53 communicating with the flash passage 27 and adapted to be detonated upon detonation of the charges in the perforating gun to drive plunger 47 downwardly shearing pin 51 and releasing balls 45. As is apparent from Fig. 1, plunger 47 has an enlarged lower end and a reduced upwardly extending stem, so that when the stem is in registry with balls 45, the balls will be forced inwardly by the downward pressure on collar 43 permitting the collar to move under the influence of gravity from the position shown in Fig. 1 to the position shown in Fig. 3.

The operation of the tool is as follows: The tool can be lowered into the well in the position in Fig. 1 with the balls 45 in locked position so that the finger carrier 33 is disposed upwardly against a shoulder or stop 19b provided on body 19 enabling the upper end of the fingers to engage the interior of the well casing. The tool is lowered into the well with the upper ends of the springs 35 sliding along the interior of the casing to approximately the position it is desired to inspect and locate collars and thereafter the tool is pulled upwardly until the upper ends of the fingers 35 enter a recess 17 and engage the lower end of a pipe section, Fig. 1 illustrating the fingers engaging the lower end 11a of upper section 11.

After engagement with the lower end of a pipe section, the upward pull on the tool can be continued to apply an increasing upward force on fingers 35 due to the compression of spring 41 and simultaneously to cam the fingers inwardly by the upward movement of sleeve 29. The resistive force of spring 41 is noted at the surface on the weight indicator and when the fingers are cammed off the pipe end, there is a sudden release of the

resistive force and a very positive indication at the surface of the location of the pipe end and therefore the location of the collar. Spring 41 will then project fingers 35 out of sleeve 29 and springs 39 will cause re-engagement of the fingers with the interior of the casing at points slightly above end 11a. Thereafter, the tool can be raised to locate the next higher collar or lowered to locate the next lower collar. Since the number of pipe sections and their lengths are known, the casing can be accurately perforated at any desired place therealong. If it is desired to perforate near the bottom of the casing, the usual procedure would be to first locate the lowermost collar and then the upper collars in turn until the depth at which it is desired to perforate is located. At other locations, the operator could proceed from the bottom upwardly or the top downwardly, or select an approximate position intermediate the top and bottom and proceed therefrom up or down.

When the desired depth is located, the charges of the perforating gun can be detonated to perforate the casing at desired points, such detonation of the charges resulting in a flame flash traveling down through passage 27 and causing detonation of charge 53. Upon detonation of this charge, plunger 47 is driven downwardly shearing pin 51 and dropping collar 43 because of inward movement of locking balls 45. As previously mentioned, light springs 39 are not strong enough to provide a sufficient frictional force between fingers 35 and the upper end of sleeve 29 to hold the fingers upwardly in the position shown in Fig. 1. Therefore, under the influence of gravity the finger carrier 33 and fingers 35 move downwardly to the position shown in Fig. 3 where the fingers are completely and permanently collapsed. The tool may thereafter be readily removed from the well without engagement between the fingers and the lower ends of the pipe sections at the collared-joints.

By the present invention, a tool has been provided whereby a perforating gun can be accurately located along a well casing to enable perforation of the casing at desired depths.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A device of the class described, comprising a body adapted to be lowered into a well casing and having an annular upwardly facing recess formed therein, a finger carrier slidably along the body and into the recess thereof, a plurality of fingers on the carrier engageable with the well casing for locating the collars, springs urging said fingers outwardly and having insufficient strength to support said fingers in their operative positions against the

force of gravity acting on the carrier and fingers, a strong compression spring normally supporting the carrier in the upper portion of the recess with the fingers in operative positions extending outwardly over the top of the recess, a collar upon the body providing a releasable support for the strong spring, means including a shear pin supporting the body, and means for shearing the pin.

2. A device of the class described, comprising a body adapted to be lowered into a well casing, a sleeve secured to the body and partially enclosing the lower portion thereof to provide an annular upwardly facing recess formed thereon, a finger carrier slidably along the body and into the recess, a plurality of fingers on the carrier engageable with the well casing for locating the collars, springs urging said fingers outwardly and having insufficient strength to support said fingers in their operative positions against the force of gravity acting on the carrier and fingers, a strong compression spring yieldably supporting the carrier in the upper portion of the recess with the fingers in operative casing-engaging positions, a collar slidably mounted upon the body within the recess to provide a support for the strong spring, a latch normally holding the collar against downward movement within the recess, a shear pin connecting the latch means to the body, and detonatable means operable to shear the pin.

3. A device for locating a joint of a well casing comprising a tubular body provided with means for attaching the body to a well tool, a finger carrier slidably mounted upon the lower end of the body, fingers upon the carrier, said fingers being spring actuated toward an outwardly extending position for engagement with the casing, a collar slidably mounted upon the body below the carrier, a spring between the collar and the carrier for resiliently supporting the carrier, a sleeve secured to the lower end of the body and extending upwardly over the collar and carrier into engagement with the fingers, latch means mounted upon the body and normally holding the collar in operative position with the spring yieldably supporting the carrier with the fingers spread outwardly into engagement with the casing, a stem within the body having a portion normally holding the latch means in collar retaining position, a shear pin securing the stem in its normal position, and detonatable means controlled from the surface of the well for severing the shear pin.
